UNITED STATES PATENT OFFICE.

CHARLES G. BABCOCK, OF LANDER, PENNSYLVANIA.

DESIGN FOR A CREAM-COOLER.

SPECIFICATION forming part of Design No. 35,206, dated October 22, 1901.

Application filed September 9, 1901. Serial No. 74,867. Term of patent 14 years.

To all whom it may concern:

Be it known that I, CHARLES G. BABCOCK, a citizen of the United States, residing at Lander, in the county of Warren and State of Pennsylvania, have invented and produced a new and original Design for a Cream-Cooler, of which the following is a specification.

This invention relates to a new and original design for a cream-cooler, and the essential features reside in the design as illustrated in the accompanying facsimile drawings, wherein—

Figure 1 is a perspective view of a cream-cooler embodying the features of the design. Fig. 2 is a transverse vertical section of the same.

The design is characterized by an elongated rectangular body 1, having a horizontally flat bottom 2, with opposite upstanding parallel flanges 3, forming sides and arranged at right angles to the bottom 2, the said flanges having upper outturned terminal rolls 4. The

one end of the body has an upstanding rectangular closure 5 and the opposite end is open, an obliquely-arranged tubular member 25 6 being disposed adjacent to the closure 5, and a tubular member 7 depends from the bottom 2, near the opposite end of the device. Over the bottom 2 a flat top 8 is arranged in parallel relation thereto and forming a flat 30 conduit 9, which extends from one end of the device to the other.

Having thus described the invention, what is claimed as new is—

The design for a cream-cooler, herein shown 35 and described.

In testimony that I claim the foregoing as my own I have hereto affixed my signature in the presence of two witnesses.

CHARLES G. BABCOCK.
